Des. 195,006
Patented Apr. 9, 1963

195,006

CONTAINER FOR DAIRY PRODUCTS

OR THE LIKE

Clara Virginia Eicholtz, Midland, Mich., assignor to The Dow Chemical Company, Midland, Mich., a corporation of Delaware

Filed Nov. 17, 1961, Ser. No. 67,570

Term of patent 14 years

(Cl. D58—17)

Fig. 2

Fig. 4

Fig. 1

FIGURE 1 is an elevational view of a container for dairy products or the like showing my new design;

The side of the container not shown is the same as that illustrated.

I claim:

The ornamental design for a container for dairy products or the like, as shown and described.
